UNITED STATES PATENT OFFICE.

RALPH L. SNOW, OF PAWTUCKET, RHODE ISLAND, ASSIGNOR TO PAYE & BAKER MANUFACTURING COMPANY, OF NORTH ATTLEBORO, MASSACHUSETTS, A CORPORATION OF MASSACHUSETTS.

DESIGN FOR A HANDLE FOR SPOONS, FORKS, OR SIMILAR ARTICLES.

44,694.

Specification for Design.

Patented Sept. 23, 1913.

Application filed July 16, 1913. Serial No. 779,397. Term of patent 3½ years.

To all whom it may concern:

Be it known that I, RALPH L. SNOW, a citizen of the United States, residing at Pawtucket, in the county of Providence and State of Rhode Island, have invented a new, original, and ornamental Design for a Handle for Spoons, Forks, or Similar Articles, of which the following is a specification, reference being had to the accompanying drawings, forming part thereof.

Figure 1 is a view showing the obverse

side of the handle in which my new design is incorporated; Fig. 2 shows the reverse side.

I claim:

The ornamental design for a handle for spoons, forks or similar articles, as shown.

RALPH L. SNOW.
